US0D1088846S

(12) **United States Design Patent** (10) **Patent No.:** **US D1,088,846 S**
(45) **Date of Patent:** **** Aug. 19, 2025**

(54) **LOAD BINDER**

(71) Applicant: **Emerald Technical Services, Inc.,**
Greenwood, SC (US)

(72) Inventor: **Robert G. Fisher, Jr.**, Hodges, SC
(US)

(73) Assignee: **Emerald Technical Services, Inc.,**
Greenwood, SC (US)

(**) Term: **15 Years**

(21) Appl. No.: **29/902,451**

(22) Filed: **Sep. 13, 2023**

(51) **LOC (15) Cl.** **08-05**

(52) **U.S. Cl.**

USPC **D8/44**

(57) **CLAIM**

The ornamental design for a load binder substantially as shown and described.

DESCRIPTION

FIG. 1 is a front perspective view of a new, original, and ornamental design of a load binder in accordance with the present design;

FIG. 2 is a left side elevation view thereof;

FIG. 3 is a right side elevation view thereof;

FIG. 4 is a back elevation view thereof;

FIG. 5 is a front elevation view thereof;

FIG. 6 is a top plan view thereof; and,

FIG. 7 is a bottom plan view thereof.

The portion of the article between the break lines forms no part of the claimed design.

1 Claim, 4 Drawing Sheets
